RACK FOR COOLING FRESHLY GALVANIZED PIPE

Oscar R. Olson, Pittsburgh, Pa.

Application April 22, 1953, Serial No. 350,371

2 Claims. (Cl. 198—84)

This invention relates generally to apparatus for treating articles such as for cooling coated articles or permitting newly made articles to set and more particularly apparatus for retaining freshly coated or new articles until they have set or their coat has cooled sufficiently to solidify and permit handling.

When making resinous plastic rods and tubes or when coating articles such as in galvanizing, tinning, or other similar coating, the handling of freshly produced products give rise to many problems. If the articles are immediately handled or stacked, the hot coating is scraped or rubbed off or they stick together causing a rupture of their surfaces thus defeating the purpose of coating. Such articles have to be re-treated or discarded. It is not advisable to recoat galvanized products without re-cleaning the article such as by pickling.

It is desirable to retain the freshly coated articles in alignment and spaced from each other to avoid any rupture of their surface or sticking to each other until after their coat becomes hardened by cooling or setting.

It is also desirable to receive the articles in substantially the same inclination that they are being handled or delivered to prevent nicking or otherwise bumping the surface by letting the articles drop a measurable distance.

The principal object of this invention is the provision of apparatus for receiving freshly formed or coated articles in substantially the same inclination that they were being treated and with minimum contact therewith and to carry or store said articles in spaced relation for a sufficient period of time to permit their coatings to become fixed such as by cooling or solidifying to permit handling and stacking. This may be accomplished by means of a movable rack which can be constructed in the form of a ferris wheel having individual pockets in which the articles are carried. If there is insufficient elevation, the rack may be in the form of a longitudinal storing means which carries the articles in a circuit or shoves them by an abutment to move or roll each article along a predetermined distance until it is ready for handling. If the article has an angular surface such as a square bar, it may be carried and rolled intermittently. If the structure is cylindrical in such a pipe, it may be rolled along the skidway by bumping intermittently or by a moving abutment. The rolling action of a cooling article prevents the newly made article or a coated article from taking a set in one direction due to its being pliable because of lack of setting time or due to the heat retained by the article depending upon the character of the article.

Ordinarily it is not necessary to convey the articles to another location during this treating or cooling cycle so the rack may discharge the articles at substantially the same place as originally received them. Thus, these racks merely retain the article a sufficient length of time to permit them to be air cooled or cooled by a blast of cold air and at the same time revolving them to prevent their taking a set due to being pliable because they are

2

soft from insensible heat. The rolling of cylindrical articles aids in retaining their shape.

Other objects and advantages appear hereinafter in the following description and claims.

5 The accompanying drawings show for the purpose of exemplification without limiting the invention or claims thereto certain practical embodiments illustrating the principles of the invention wherein:

10 Fig. 1 is a view in side elevation of the cooling rack comprising this invention.

Fig. 2 is a plan view of the structure shown in Fig. 1.

Fig. 3 is a view of the left end of Fig. 1 showing the charge and discharge end of the cooling rack comprising this invention.

15 Fig. 4 is a view of the opposite or right end of the rack illustrated in Fig. 1 showing a transfer mechanism for delivering the articles from the upper to the lower level of the rack.

Fig. 5 is a detailed view of the pusher.

20 Referring to the drawings, the cooling rack consists of the side frame members 1 and 2 that are formed by a series of vertical posts 3 tied together by the cross brace members 4 joined by the center gusset plates 5 and the upper and lower gusset plates 6 and 7. These sides are 25 braced with one another by the knee braces 8 that are fastened from the posts to the upper cross members 10 as shown in Fig. 3, which carries the upper flight of articles. One end of the frame has the cross braces 11 as shown in Fig. 4 which are also provided with gusset plates joining the parts.

Intermediate cross members 12 together with the cross members 13, 14, and 15 connect the side frames to brace the structure and carry the articles along the lower flight.

35 The cross members 10 and 12 support the longitudinal channels 16 and 17 for the top flight and the channel guides 18 and 19 for the return flight of the top pusher. These channels carry the pusher or drag chain 20 provided with upwardly projecting abutments 21 that roll the article such as the tube 22 along the rack before the 40 abutment.

The drag chains 20 travel over the independently mounted sprockets 23 and 24 at the left or receiving end and the sprockets 25 and 26 on a suitably journaled shaft 27 at the right end of the top flight. This shaft extends 45 beyond the side frame 1 and is provided with the sprocket 28 that receives the drive chain 30 that passes over the idler sprockets 31 and 32 in turn and over the driver sprocket 33 on the shaft 34 journaled in the lower flight.

The shaft 34 extends across the frame and is provided 50 with spaced sprockets 35 and 36 which carries the chains 37 and 38 that are similar to the chains 20 and have similar abutments 21. The chains 37 and 38 travel in the upper channels 40 and 41 to the left end of the rack where they pass around the sprockets 42 and 43 mounted on the shaft 44 that is journaled in the side frames in the same manner as the other shafts 27 and 34. The channel members 40 and 41 may slope downwardly to the left in Fig. 1. The chains 37 and 38 pass down around the 55 sprockets 42 and 43 and return through the channel guides 45 and 46 to the sprockets 35 and 36 at the right end of the rack.

The shaft 44 extends beyond the frame 1 and is provided 60 with a drive pulley 47 which may be in the form of a multiple V-belt pulley that is driven by the multiple belt means 48 to the small pulley 49 on the speed reducing mechanism 50 which in turn is driven by the motor 51 through the torque converter 52.

Thus the motor 51 drives the shaft and the sprockets 65 42 and 43 thereon drive the endless chains 37 and 38 which in turn drive the sprockets 35 and 36 on the shaft 34 which drives the top shaft 27 through the drive chain 70

30, and the top shaft drives the endless drag chains 20 through the sprockets 25 and 26. This drive starts at the delivery end of the rack and extends to the loading end.

The articles handled are indicated by the pipe sections 22 that are retrieved from a salt or spelter tank by the magnetic rolls 54 and 55 and other similar rolls making up a series. These rolls are supported from the frame 56 that may be moved from the vicinity of the tank or rack.

The tubes are cleaned as they are removed from the kettle and are laid on the inclined slope of the rack formed by the disposition of the top channels 16 and 17 which slope downwardly toward the right as shown in Fig. 1 and these skids or channel members are declined to the same horizontal plane which is also shown in Fig. 1. The tubes 22 are carried around the sprockets 25 and 26 while resting against the guide tracks 57 and 58 which deposits the tube on the top flight of the lower set of channels 40 and 41 where the chains 37 and 38 move the tube along these channels to the discharge that permits the tube to roll in turn onto the storing table 60 or any other form of storing or loading device. The channels 40 and 41 slope slightly to the left to augment the rolling of the tubes by the pusher.

In its travel along this rack, the tube 22 has been returned to substantially the same point that it was loaded on the rack. The tube has been rolled or pushed along and not permitted to take a set or rest sufficiently to draw the coating all to one side but kept uniform with a minimum surface engagement, namely, the upper edges of the channels. This provides for controlled setting or cooling of the particles. The speed of their removal and the speed of their circuit through the rack may be controlled to properly treat these articles.

The articles may be treated by a blast of air from the fan 61.

I claim:

5 1. A rack for cooling lengths of freshly galvanized pipe sections which comprises, a frame with upper and lower track levels and a transfer therebetween at one end, a pipe receiving station on the upper track level and a pipe discharge station on the lower track level at the opposite end of said frame from said transfer, conveyor means along said track levels having spaced abutments to shove separated pipe sections from the receiving to the discharge station and causing the pipe sections to rotate due to their frictional contact with the track to maintain a uniform distribution of the galvanize before it cools 15 and hardens, said upper track level being disposed on a lateral slope at the pipe receiving station and horizontal at said transfer end, whereby to drain any excess galvanizing fluid from the rotating pipe sections and to match the inclination of the pipe sections when delivered 20 at the receiving station.

2. The structure of claim 1 characterized in that the track on the upper level slopes from said pipe receiving end to said transfer end.
